UNITED STATES PATENT OFFICE

165,887

LUGGAGE RACK OR SIMILAR ARTICLE

Frank Troccoli, Chicago, Ill., assignor to Waco Products, Inc., Chicago, Ill., a corporation of Illinois

Application January 20, 1950, Serial No. 7,366

Term of patent 14 years

(Cl. D33—14)

To all whom it may concern:

Be it known that I, Frank Troccoli, a citizen of the United States, and a resident of Chicago, in the county of Cook and State of Illinois, have invented a new, original, and ornamental Design for a Luggage Rack or Similar Article, of which the following is a specification, reference being had to the accompanying drawing forming a part hereof.

In the drawing the single figure is a perspective view of a luggage rack or similar article showing my new design.

I claim:

The ornamental design for a luggage rack or similar article, substantially as shown.

FRANK TROCCOLI.
